UNITED STATES PATENT OFFICE.

JACOB KAPPLER, OF PHILADELPHIA, PENNSYLVANIA, ASSIGNOR TO GILL & CO., INC.,
OF PHILADELPHIA, PENNSYLVANIA, A CORPORATION OF PENNSYLVANIA.

DESIGN FOR A GLASS SHADE, REFLECTOR, OR SIMILAR ARTICLE.

46,742.

Specification for Design.

Patented Dec. 8, 1914.

Application filed September 10, 1914. Serial No. 861,152. Term of patent 7 years.

To all whom it may concern:

Be it known that I, JACOB KAPPLER, a citizen of the United States, residing in the city and county of Philadelphia, State of Pennsylvania, have invented a new, original, and ornamental Design for Glass Shades, Reflectors, or Similar Articles, of which the following is a specification, reference being had to the accompanying drawing, forming part thereof.

Figure 1 is a side elevation of a glass

shade, reflector or similar article, showing my new design. Fig. 2 represents a bottom plan view thereof.

I claim:

The ornamental design for a glass shade, reflector or similar article, as shown.

JACOB KAPPLER.
